STRETCHER

Malcolm R. Peters, San Mateo, Calif.

Application November 18, 1941, Serial No. 419,594

11 Claims. (Cl. 5—82)

1

This invention relates to stretchers, and has for objects the provision of a compact, light weight, strong and rigid stretcher that is economical to make, and which stretcher is provided with means for securing an injured person thereon for carrying horizontally in the usual manner, or for hoisting the stretcher when in horizontal, vertical or in inclined position, suspended from a hoist line.

Another object of the invention is a stretcher provided with float means for supporting a person thereon in the water in inclined position with the head of the person well above the water level.

Other objects and advantages will appear in the description and drawings annexed hereto.

On shipboard and in mines, industrial plants, and in many other places, it frequently happens that persons are incapacitated by injuries, or are overcome by some agency or illness, when such persons are in places where their removal on ordinary stretchers is impossible, or is extremely difficult even though no particular difficulty may be encountered in getting the stretchers to such places. For example, in a tank, or in the hold of a ship where the sole access by a person into such tank or hold is through an overhead opening not much larger than the thickness of the body of such person, it is of no value to pass an ordinary stretcher into such opening, since the stretcher with the person thereon cannot be removed through said opening.

The ordinary practice heretofore, has been to either pass a rope around the injured person's body below the arms and to then pull him or her through the opening, or another person may carry the injured one to the opening, but in either case, the injured person frequently receives further injuries due to being improperly handled.

My stretcher is capable of being secured to a single rope and lowered through an opening of substantially the thickness of the body of a person, and the injured person may be then laid on the stretcher and secured thereto after which the stretcher is hoisted by said rope through the opening, and the weight of the person on the stretcher is supported principally on bands enclosing the lower limbs. Also, the means for securing the person to the stretcher may pass over the upper arms, or under the upper arms, as desired, so that the arms may be held down or left free, according to the character of the injury, and when left free, the weight of the person may be supported on the stretcher by the band passing below the arm pits, should any reason exist for leaving the legs unsecured.

2

In hoisting a person from on board a ship to another ship or boat, a single line may also be used, and means is provided for supporting the stretcher horizontal, or inclined, or vertical, whichever position is most comfortable for the injured person, and in any position the injured person may be substantially immovably secured to the stretcher so as to guard against injury during the transfer, and before or after the transfer is effected.

In the event of shipwreck or where circumstances make it imperative that the ship be abandoned, the stretcher is provided with float means so positioned as to support the injured person on the stretcher in inclined position in the water with the head of such person well above the water level.

In the drawings:

Fig. 1 is a plan view of my improved stretcher, with the ropes indicated in single line for clarity, and in which concealed or covered elements are indicated in dot-dash lines while stitching is indicated in short dash lines. Also, where one rope passes over the other, conventional crossing symbols as used to indicate crossing pipes or wires are used. Parts of the figure are broken away to reveal normally concealed structure.

Fig. 2 is an enlarged sectional view taken along line 2—2 of Fig. 1.

Fig. 3 is a sectional view of lesser enlargement than that of Fig. 2, taken along line 3—3 of Fig. 1.

Fig. 4 is a sectional view taken along line 4—4 of Fig. 1.

Fig. 5 is a perspective view showing my stretcher in use being swung in one position in which the stretcher is inclined relative to horizontal.

Fig. 6 is a perspective view showing my stretcher in use being horizontally supported.

Fig. 7 is a front view of my stretcher in use when vertically supported with a person thereon.

In detail, my stretcher comprises an elongated frame, preferably formed from a metal tube for lightness and strength. This frame is enclosed in a canvas covering providing an upper side 2 and a lower side 3 spaced apart by the end and side members of the frame. This canvas covered frame forms the main body of the stretcher. The side members of the frame extend divergently from one of the end members to the other, and the end members are parallel. The narrower end of the frame is the foot, while the wider end is the head, and the degree of divergence of the side members corresponds generally to the progressively increasing width of a person's body from the feet to the shoulders of such person,

and which divergence is sufficient to enable the arms of such person to rest on the stretcher along the side frame members when the arms extend along the sides of the person and substantially against the body.

The elements secured to the upper side of the canvas covering will be described first.

On the head portion of the frame are secured a pair of spaced, parallel bands 4 extending longitudinally of the frame, between which bands the head of an injured person on the stretcher is adapted to rest on the top side 2. Bands 4 are secured centrally between their ends to the upper side 2 by stitching 5, or any other suitable means, and are secured by similar stitching 6 to side 2 at their opposite ends, thus providing for passing a bandage, handkerchief or other like means between the bands 4 and side 2 at either of the sides of stitching 5, and then over the forehead of a person to hold the head against side 2.

Below the lower ends of bands 4 (which ends are nearest the foot of the frame), is a relatively wide band 7 of flexible material extending transversely across the stretcher and extending equal distances outwardly of the side members of the frame. This band secured to side 2 by stitching 8, or by any other suitable means in a position so that the upper edge adjacent bands 4 will be at about the level of the arm pits of a person on the stretcher, and the width of the band is such that the opposite end portions, when brought around the body of such person will substantially enclose the upper portion of said body with the outer ends of the band spaced slightly apart, as best seen in Fig. 7.

Enclosed in the opposite ends of band 7 are rigid strips 9 (Fig. 3) of wood or of any other relatively light material, which strips are preferably flat on their sides adapted to be adjacent the body of a person on the stretcher when the bands are brought over such body. The opposite sides of said strips may be rounded, as indicated in Fig. 3.

Secured to one end of band 7 is a pair of spaced loops 10 of flexible, tape-like material, while at the opposite end, is a pair of similarly positioned straps 11 of the same material. These straps and loops may be of double thickness so as to extend over opposite sides of the band 7 at one of their ends, and also over opposite sides of the stiffener strips 9, as indicated in Fig. 3, with the double layers stitched together securing marginal portions of band 7 therebetween.

Spaced below band 7 is another relatively wide band 12 of flexible material, such as canvas. This band 12 may be slightly wider than band 7, so as to extend from about the knees of a person on the stretcher, to about the widest portion of the hips. The opposite end edges of band 12 extend divergently upwardly from the lower edge, or from the edge of the band nearest the foot of the stretcher, and its length is preferably slightly less than that of band 7.

Along the opposite edges of band 12 are stiffener strips 9', secured adjacent said edges the same as the stiffener strips 9 on band 7, as indicated in Fig. 3. At one of the ends of band 12 are a pair of loops 10' secured to the band in the same manner as the loops 10, which loops 10' are also of tape-like, flexible material, while at the opposite end of the band is a pair of straps 11' that are substantially identical with straps 11.

It is pertinent to note that the band 12 is stitched or secured to side 2 of the stretcher along lines 13 extending divergently in direction

from the foot of the stretcher toward the head.

Below band 12 is a third band 14 that is relatively short, and which band is secured to side 2 along substantially parallel lines inwardly of the sides of the frame, as by stitching 15. Secured to the opposite ends of this band are strips 9'', corresponding to the stiffener strips 9, band 7, while at one end edge a loop of tape-like material 10'' positioned about midway between the longitudinal edges of band 14, while a strap 11'' is secured to the opposite edge of the band about midway between said longitudinal edges. This band 14 is positioned to substantially encircle the lower limbs of a person on the stretcher between the feet and knees.

Figs. 5 to 7 illustrate the positions of the bands 7, 12, 14 in position securing an injured person 16 on a stretcher, in which the head is secured by a flexible strap 17 or any similar means passing between the upper portion of bands 4 and the stretcher. If the person were shorter, the strap 17 would be passed between the lower portion of the bands and the stretcher, below stitching 5.

The covering of the stretcher is preferably of canvas, as are the bands 7, 12, 14 and the various loops 10, 10', 10'' and straps 11, 11', 11'', as well as bands 4 may be of softer and more flexible fabric.

In securing a person on the stretcher, the straps 11, 11', 11'' are passed through loops 10, 10', 10'', respectively, and are drawn up as tightly as may be desired, after which the free end portions of the straps are tied at the loops in any conventional, quickly releasable knot.

The lengths of bands 7, 12, 14 are such that the end edges at stiffener strips 9, 9' and 9'' will be spaced slightly apart, where a relatively small adult is on the stretcher, so as to permit the bands to be drawn tightly around the body of such person or any larger person. It is pertinent to note that the bands 7, 12, 14 are stitched or secured to the top side 2 of the stretcher at points spaced inwardly from the side frame members of the stretcher so as to permit considerable latitude in accommodating the bands to various sized persons, any of which can be securely held on the stretcher.

Where it is desirable to secure a child, or an extremely small adult to the stretcher, I secure a pair of loops 18 to the side 2 adjacent one of the side edges of the frame, which loops are spaced to correspond to the spacing between loops 10. One of the ends of each of said loops is secured to the side 2 by the same stitching that secures band 7 to said side.

A similar pair of auxiliary loops 19 are secured below band 12 and are secured at one of their ends to the side 2 by the same stitching that secures band 12 to side 2.

Thus, when a child is placed on the stretcher, the ends of bands 7, 12 that carry loops 10, 10' are brought over the body of the child, and the opposite ends of said bands then overlap the ends carrying said loops 10, 10'. The straps 11, 11' are then passed through loops 18, 19, respectively and are then tightened and tied.

The foregoing description is complete with respect to the elements carried solely by the top side 2 of the stretcher, and the following description is to the elements carried by the lower side 3.

Between sides 2, 3 and on side 3 are a plurality of elongated stiffener slats 20 that are spaced apart and that extend longitudinally of the stretcher from the foot portion to the head

portion, terminating at their ends short of the ends of the stretcher frame.

Extending over the ends of these slats, which may be of hardwood, or of any other suitable material, are canvas strips 21 (Fig. 3) that are stitched to side 3 beyond the ends of the slats and between the slats, as well as adjacent the opposite outermost edges of the outer slats, thus forming individual pockets in which the ends of the slats are positioned. Thus, when the stretcher is laid flat on the floor or other supporting surface with a person on the top side 2, the slats will support the body of such person elevated slightly above the floor, and will also support the body, in conjunction with the side 2, when the stretcher is supported elevated from the floor so as to prevent outward bulging of the lower side of the stretcher in its tendency to conform to the contour of the person thereon.

Also secured to lower side 3, I provide a pair of cylindrical shaped float members 22, which may be made of any desired buoyant material enclosed in canvas. These cylindrical floats are disposed below band 7, and are used where the possibility is imminent that injured persons may have to be placed in water, as where such persons are on shipboard and the ship must be abandoned before assistance is at hand to effect a transfer to another ship. Also, even where transfers are to be made from one ship to another or to a boat, etc., the floats function to keep the person on the stretcher afloat in the event of accident in effecting the transfer, and the stretcher is dropped into the water.

These floats 22 may be secured to the side 3 in any suitable manner, as by tape members 23 that may be sewed to the ends of the floats and to the side 3. The ends that are secured to the floats may extend under the coverings of the ends of the floats (Fig. 6). The position of these floats is adjacent the side frame members of the stretcher below the band 7, in which position, when the stretcher is in the water, the floats will support the body of the person on said stretcher in inclined position, about that indicated in Fig. 5, in which the head of the person is well above the water level.

The foregoing completes the description of the elements secured to, or solely carried on the bottom side 3 of the stretcher.

The following description relates to elements principally secured to the frame of the stretcher.

At the foot of the stretcher and adjacent the side frame members, the sides 2, 3 are formed with registering openings 24, 24' reinforced by grommets or in any suitable manner. The numerals 24, 24', each pair of registering openings, and in all openings in the top and bottom canvas sides hereinafter referred to for securement of elements, or parts of elements, to the frame, each pair of registering openings have reinforcing grommets or other reinforcing means around the edges of the openings.

A rope 25 is secured at one end to the frame, extending at said end through registering openings 24 at one side of the frame, and then around the side frame member at said side, and back to the body of the rope to which the said end is spliced or lashed. From openings 24 the rope extends outside the stretcher alongside the side member of the frame to the end of the stretcher at its head, being successively secured to the side member of the frame that is adjacent openings 24 at spaced points 26, 27, 28, 29, 30 in direction from the foot of the stretcher toward the head.

The length 31 of said rope that extends between points 24, 26 is relatively slack, while the length extending from points 26 to 29, and past points 27, 28, is straight and close alongside the side frame member. Between points 29, 30 the rope 25 is again relatively slack, as at 32. At each of the points 26 to 30, the rope 25 is lashed to the frame, or otherwise secured thereto, by lashings extending through registering openings in sides 10, 2, 3 of the stretcher alongside the stretcher frame. These openings are reinforced the same as opening 24.

The opposite end of rope 25 is secured to the side frame member that is across from openings 15 24, as at 24' and said rope is similarly secured to said frame member at points 26', 27', 28', 29' and 30', which points are directly across the stretcher from openings 26 to 30. Slack portions 31' and 32' are provided between openings 24', 26' and 29', 30', corresponding to slack portions 31, 32.

From openings 30, 30' the rope 25 extends over the head end of the stretcher in a slack portion 33. Thus, upon securing a hoist rope 33' (Fig. 7) to portion 33, the stretcher with a person thereon can be hoisted in vertical position through a relatively small hole of a diameter substantially the maximum width of the stretcher.

A second rope 34 is secured to the side frame 30 member of the stretcher adjacent openings 24, as at point 35, in the same manner as one end of rope 25 is secured to said member at 24. Openings 35 are positioned relatively close to openings 24, between openings 24, 26.

From openings 35 the rope 34 extends freely along the side frame member of the stretcher through the opening or loop formed by slack portion 32 of rope 25, and the opposite end of the rope extends through openings 35' adjacent openings 24' and is secured to the opposite side frame member of the stretcher and from said openings 35' the rope extends freely along the said opposite side frame member and through the loop formed by slack portion 32' of rope 25.

The rope 34, after passing through the loops formed by slack portions 32, 32', extends across the opposite ends of a rigid bar 37, to which ends the rope is secured by lashing or in any other desired manner. This bar 37 is parallel with 50 the end frame member of the stretcher at the head of the latter, and is of a length to enable the rope 34 to clear the stretcher upon swinging the bar across said end frame member to the forward or rear side of the stretcher.

From the ends of bar 37 the rope 34 extends convergently outwardly relative to the stretcher, and is formed with a bight 38 for securing to a hook or hoist rope 39 (Fig. 5).

When a hoist 39 is secured to bight 38, and the 60 stretcher is hoisted, the rope 34 will support the stretcher in inclined position (Fig. 5) by reason of its passing through the loops formed by the portions 32, 32' of rope 25. The principal weight of the stretcher, and person thereon, will be carried from the bottom of the stretcher, however, as rope 34 is secured directly to the foot end of the stretcher.

When the rope 34 is not in use for hoisting, bar 37 may be tied to the head end of the stretcher frame by cords or tape-like pieces 40 (Fig. 1) that are carried by the head end of the stretcher.

When the rope 34 is in use for supporting the stretcher in inclined position, I prefer to connect the rope at opposite sides of the frame by a rela-

tively wide band 41 (Fig. 5), which band may be permanently secured at one end or the other to the length of rope at one side of the frame, on which length it may be rolled, and secured by tie strips 42 secured to the opposite free end of said band. These tie-strips are then used, when the band is unrolled, for securing to the rope 34 as indicated in Fig. 5. Band 41 is positioned to extend across the chest of a person on said frame, and functions to stabilize the rope 34 during hoisting, as well as prevent the possibility of the frame incorrectly supporting the injured person in improper inclined position in the event of rough handling, since the stretcher otherwise might accidentally pass between the parallel runs of rope 34 to the side opposite that shown in Fig. 5.

In hoisting the stretcher horizontally, as seen in Fig. 6, the bar 37 is slipped over the head of the stretcher to below the head of the injured person thereon, and then the parallel runs of rope 34 are brought together about centrally of their ends and are secured to hoist rope 39 by a non-slipping knot.

In the event the stretcher is to be carried horizontally, the loops or slack portions 31, 31' and 32, 32' at the foot and head of the stretcher provide hand grips for attendants to carry the stretcher.

From the foregoing description, it is seen that the stretcher can be carried by attendants in horizontal position the same as any stretcher, or it can be hoisted horizontally, vertically or in inclined position, as desired, all by means of the rope arrangement, and in the event it is in the water, the stretcher will properly support a person thereon in a relatively safe and comfortable position until the stretcher is removed from the water, which removal is readily accomplished by means of a hoist rope connected to bight 38 or to portion 33, the latter being exposed at all times for connecting the rope thereto, or for manual grasping.

The specific details herein described are not intended as limitations, but are illustrative of a structure adapted to accomplish the results described.

Having described my invention, I claim:

1. An elongated stretcher having a head end and a foot end respectively at its opposite ends; means for securing the extended body of a person thereon; a rope having opposite end portions respectively extending along each of the longitudinal edges of said stretcher and a central portion of sufficient length to project outwardly beyond the head end of said stretcher for suspending the stretcher vertically from the latter; the opposite ends of said rope being secured to said stretcher adjacent said foot end and a pair of eye members secured to said stretcher adjacent the head end thereof and adjacent the opposite side edges through which said rope is slideable, said rope being of a length to enable swinging of said end portions at points respectively between the said eye members and the ends of said rope for engagement at a point about centrally over said stretcher when said end portions of the rope are drawn taut with the central portion of the rope below the head end of the stretcher for suspending said stretcher substantially horizontal from such points.

2. An elongated, relatively flat stretcher adapted to support the extended body of a person thereon with the head adjacent one end thereof and the feet adjacent the opposite end; flexible

means secured to the stretcher at points adjacent the opposite longitudinal edges of the latter and relatively close to the foot end of the stretcher; said means extending longitudinally of the 5 stretcher along said edges toward the head end of the stretcher and projecting outwardly beyond said head end; means spaced from the head end of said stretcher connecting the projecting ends of said flexible means; said flexible means being 10 free for swinging about their points of securement to the foot end of said stretcher transversely of the plane of the stretcher to one or the other side of said stretcher; means for securing the projecting ends of said flexible means at 15 a single point to a single hoist rope for suspending said stretcher in generally vertically extending position; and means limiting said movement of said flexible means about their said points of securement for supporting said stretcher, inclined relative to vertical when said stretcher is suspended by said flexible means from such hoist rope.

3. In a construction as defined in claim 2, said 25 flexible means comprising a first rope; the means for limiting the movement of said flexible means comprising a second rope connecting between said first rope and the head end of said stretcher.

4. An elongated stretcher adapted to support the 30 extended body of a person thereon with the head adjacent one end thereof and the feet adjacent the opposite end; a single rope secured at opposite ends to the foot end of said stretcher adjacent the longitudinal side edges of the latter; said rope extending along said side edges to the 35 head portion of said stretcher and outwardly of said head portion to beyond and over the latter for securing of a hoist rope to the projecting portion of said rope for hoisting said stretcher; a second rope secured to said stretcher along 40 said edges of the latter, a portion of said second rope adjacent said edges and adjacent the head and foot portions of said stretcher being relatively slack for grasping of said slack portions by an operator for carrying said stretcher horizontally; means comprising the slack portions of 45 said second rope that are adjacent said head portion of the stretcher limiting the swinging of said single rope about its ends that are secured to said foot portion whereby said stretcher, when hoisted by such hoist rope, will be suspended in inclined position with the head portion uppermost.

5. An elongated stretcher adapted to support the 50 extended body of a person thereon with the feet adjacent one end thereof and the head adjacent the opposite end; means secured to said stretcher and projecting therefrom for suspending said stretcher in generally vertically extending position with the head end of said stretcher uppermost; float means secured to said stretcher adjacent said head portion for supporting said stretcher in the water in inclined position with the head portion thereof above the water level for supporting a person secured on said stretcher 55 with his head above said level; means for securing a person on said stretcher; and the means for suspending said stretcher being secured to said stretcher adjacent the foot end of the latter and extending past said float means to a point beyond the head end of the stretcher.

6. A stretcher including a pair of elongated side frame members, and a pair of end frame members, respectively connecting between corresponding ends of said side frame members, providing 60 an elongated, centrally open frame, and a sheet

of fabric secured to said side and end frame members and extending therebetween for supporting a person thereon; a first rope secured to said frame at a pair of spaced points adjacent one of said end members and freely extending therefrom along each of said side frame members and outwardly beyond the opposite end member; a second rope secured to said frame at a pair of spaced points respectively positioned adjacent said first mentioned pair of points and extending therefrom along each of said side frame members and outwardly beyond said opposite end member; said second rope being formed with a pair of loops adjacent each of said end members and projecting from said side frame members, and the 15 rope forming each of said loops being secured at the ends of each loop to said side frame members; said first rope at each of said side frame members being in a position extending through the respective loops that are adjacent said opposite end frame member whereby said latter loops will limit the lateral movement of said first rope; said first rope being arranged and adapted for 20 securing to a hoist rope positioned outwardly of said opposite end member.

7. An elongated, relatively flat stretcher adapted to support the extended body of a person thereon with the head and feet adjacent opposite ends thereof; means for securing such body thereon; a rope secured at one end to the foot portion of said stretcher and extending therefrom along one longitudinal edge of said stretcher and over the head portion of the stretcher and back to the said foot portion along the opposite longitudinal edge of said stretcher and the opposite end of said rope being secured to said foot portion; means securing said ends of said rope to said foot portion at points adjacent said edges for swinging the remainder of said rope about said points to opposite sides of the plane of said stretcher; a bar secured at its ends to the lengths of said rope that extends along said edges; said bar being positioned adjacent the head end of said stretcher outwardly thereof and spacing said lengths apart a distance slightly greater than the width of the stretcher; the portions of said rope between said bar and their points of securement to said stretcher being free for swinging to positions over one side of said stretcher when said bar is positioned across at the opposite side of said stretcher, whereby said portions may be secured to a hoist rope for hoisting said stretcher in horizontal position with said bar supporting one end of said stretcher during such hoisting, means to prevent shifting of the bar toward the foot of the stretcher.

8. In a construction as defined in claim 7, the portion of said rope extending beyond said bar outwardly of said stretcher being slack for engagement with a hoist rope for hoisting said stretcher in substantially vertical position when said bar is positioned outwardly of said end portion.

9. A stretcher including a pair of elongated side frame members and a pair of end frame members, respectively connecting between corresponding ends of said frame members providing an elongated, centrally open frame; an envelope of fabric enclosing said frame providing top and bottom sides for said stretcher spaced apart by said 70

frame; a plurality of elongated slats between said sides extending longitudinally of said frame and secured to one of said sides only; said stretcher being formed to provide a head portion at one end for supporting the head and upper body of a person on said upper side, and to provide a foot portion at the opposite end for supporting the feet and lower body of such person; means for securing the body of such person on said upper side; means secured to the foot end of said stretcher extending longitudinally of said stretcher and projecting from the head end thereof for suspending said stretcher in generally vertically extending position from the projecting portion of said last mentioned means.

10. An elongated stretcher having a head end and a foot end respectively at its opposite ends; a relatively slack length of rope extending along each of the longitudinal edges of said stretcher, 20 means securing each of said lengths at their ends to the head and foot ends of said stretcher adjacent the ends of said longitudinal edges; said lengths between their said ends being slack and sufficiently long to enable swinging of the central portion of said lengths for engagement at a point substantially centrally over said stretcher for suspending the stretcher in a generally horizontal position by said lengths from said point; a section of rope connecting said lengths at the head end 25 of the said stretcher for suspending said stretcher in a generally vertical position by said section.

11. An elongated relatively flat stretcher having a head end and a foot end respectively at its opposite ends; a centrally open frame defining the edges of said stretcher and a canvas sheet secured to said frame and stretched across the central opening of the frame; means at said head end for suspending the stretcher vertically therefrom; a flexible band extending transversely across said stretcher about centrally between its ends and positioned to substantially encircle the portion of such body below the hips and above the knees; means securing said band to said canvas sheet along lines spaced inwardly from the 35 longitudinal edges of said stretcher and spaced from each other a distance less than the normal width of the body of a person whereby said band will snugly fit around such body below the hips thereof and will substantially support said body against sliding toward the foot end of the stretcher when the latter is suspended generally vertically from above said head end; means for 40 securing said band around said portion of such body; rigid means secured to said band and extending transversely thereof for stiffening said band against wrinkling; the means for securing said band around said portion of such body including a strap secured to one end of said band and a loop element secured to the other end 45 thereof; and said rigid means comprising strips of rigid material secured to opposite ends of said band said means for suspending said stretcher comprising a rope extending across the head end of said stretcher and along the longitudinal edges thereof outwardly of said lines; means for securing said rope to said canvas at the foot end of said stretcher, and loops connected with said stretcher adjacent the head end thereof through 50 which said ropes extend to said head end.

MALCOLM R. PETERS.
